(57) **CLAIM**

The ornamental design for a crane cab interior component, as shown and described.

DESCRIPTION

FIG. 1 is a top perspective view of a crane cab interior component showing our new design in an assembled condition;

FIG. 2 is a front perspective view of a crane cab interior component showing our new design in an unassembled condition set apart from the cab of FIG. 1 for ease of illustration;

FIG. 3 is a rear view thereof;

FIG. 4 is a right side view thereof;

FIG. 5 is a front view thereof;

FIG. 6 is a left side view thereof;

FIG. 7 is a top view thereof; and,

FIG. 8 is a bottom view thereof.

The broken line showing of the cab in FIG. 1 is for environmental purposes only and forms no part of the claimed design. The broken line showing in FIGS. 2-8 is included for the purpose of illustrating portions of the crane cab interior component and forms no part of the claimed design.
